THADDEUS DONELY AND JOSEPH B. CRESSLER, OF SOUTHAMPTON,
PENNSYLVANIA

Letters Patent No. 73,699, dated January 28, 1868.

ADJUSTABLE SHOVEL-PLough.

The Schedule referred to in these Letters Patent and making part of the same.

TO ALL WHOM IT MAY CONCERN:

Be it known that we, THADDEUS DONELY and JOSEPH B. CRESSLER, of Southampton township, Franklin county, and State of Pennsylvania, have invented a new and useful Improvement in Ploughs; and we do hereby declare that the following is a full and exact description thereof, reference being had to the accompanying drawings, and to the letters of reference marked thereon, in which—

Figure 1 is a side view, having one wheel removed.

Figure 2 is a plan view.

Figure 3 is a rear end view of shaft and axle.

Figure 4 is a side view of main lever.

Figure 5 is a top view of one plough.

Figure 6 is a side view of same.

Figure 7, several views of levers for operating the tongue. No. 1, end view of curved catch to sustain the end of tongue; No. 2, plan view of the same; No. 3, side view, showing the upper curve, fulcrum, and foot-lever.

Our invention consists in the combination of a lever-adjustment to a series of ploughs, arranged under the axle of a pair of wheels, so that any one stock, of each set of ploughs, may be lifted at pleasure, or all may be lifted at the same time. Also in the manner of connecting this lever to a tube or hollow cylinder, upon an independent shaft, which is connected to the main axle, so that the driver, in his seat, may, by moving this lever transversely, in either direction, lead the gang of ploughs to the right or left, while the horses are continuing in the direct line, and this to an extent equivalent to any practicable distance between the wheels; and at the same time, by a forward motion of the lever, can lift all the ploughs clear from the ground, and when desirable, can drop either the right or left plough only, or all at once, as the nature of the case may demand it. This is accomplished by the use of secondary levers, working upon and near the top of the main lever, and operating upon two pawls, which are placed in a slot in the lower end of the main lever, which pawls catch hold of two rods, rigidly fixed to the tube or hollow cylinder, working around the shaft, and on the ends of which tubes are fixed arms, extending backwards and downwards, and connected to the plough-stocks beneath, by straps on each side, made movable upon rivets at each end.

Our invention also provides for a proper direction of the gang of ploughs, when it becomes necessary to carry them close to a fence, or any other object, when the team cannot draw the apparatus near enough to cultivate the ground. This is effected by another combination of levers, in such a manner that the driver, by bearing with his foot on a foot-lever, will detach from the end of the tongue a pawl, which holds it to its place, when the course of the apparatus is direct. This being removed by pressing another lever opposite to his hand, either to the right or left, he will give the wheels a direction at any angle required to bring the ploughs to the right or left, while the team can continue on the original direction; and when the necessity for this divergence shall have ceased, by reversing the motion of the lever, the tongue will resume its normal position, and the ploughs continue as before.

We also combine with these devices and the side ploughs a detachable central plough, for the purpose of checking the ground, as well as to act as a cultivator.

In the drawings, A is the axle-tree; B' is the outside frame of metal; C, the wheels; D, driver's seat; E, lugs, below the frame, supporting the shaft s¹; F, central plough; F', braces, by which it is held in place at f³; G, back bars for whiffle-trees; H, braces of metal; L, main operating-lever; P, the pawls, retaining rods p p; R, rods, connecting small levers l l with lower end of pawls P P, at v v; S S¹, tubes, working around shaft s¹; S², arms, extending from tubes S S¹, and connected to plough-stocks by straps s² s²; T, tongue of the apparatus; T¹, the lever, by which it is moved laterally; T², hand-lever, working it. a is a crane, supporting the lever L, and at a' forming the fulcrum, around which that lever works, to move laterally the tubes S S, they working freely through its lower end, e¹, which is connected firmly to the main axle-tree at e²; b is an eye, in each lower end of frame B', to which are fastened the two plough-stocks S¹, and in the straps on their ends are fastened the two ends of the straps of plough-stock F, by the hooks f³; d the spring brace,

supporting driver's seat; d^1 , the foot-support; d^2 , hand-rod and guard; e , guard-plate; e^1 , the lower end of crane, supported from the plate e^2 ; f , the stock of plough f^1 , braced by rod f^2 ; $l l$, small levers, on main lever L , working on a fulcrum at projections l^1 , having rods $R R$, connecting them with the pawls at $V' V'$; $p p$, rods, firmly connected with the tubes $S S$, by pins $u u$, figs. 3 and 4, which tubes are separated by the lower end of the lever L , which works upon the annulus t^1 , to which it is fastened by pins t^2 , in fig. 4, and which gives motion to the tubes when operated upon by the lever L to the right or left; $s s$, shaft, fastened at each end in the lugs $E E$, and on which the tubes $S S$ revolve and slide, when operated upon by the lever L ; $t t$, the segment of a circle, fastened into the frame B , on the lower side, immediately under the brace H , at $h h$, by the same bolt. This segment passes through the end of the tongue T , at t , fig. 7, Nos. 2 and 3, and serves as a guide for the tongue, when operated upon by the lever T^2 ; t^1 is a curved lever, bent in several directions, and having at the tongue T two raised surfaces, $t^2 t^3$, and a square joggle, to fit the width of the tongue, and in which it rests, and is held firmly until it is required to move the tongue, when, by depressing the end, t^3 , the curved part t^2 is lowered, and the tongue can be moved laterally, by the lever T^2 acting on the horizontal lever T^1 , which has one end fastened by a movable nut, on the top of the tongue T , No. 1, fig. 7, at t^4 ; $v v$, lower end of pawls $P P$, into which the lower ends of rods $R R$ are linked; $v' v'$, springs, fastened into pawls at $V' V'$, and passing through the slot in lever L , and which keep the pawls down, they being pivoted by a pin, p^2 .

Having described the several parts of these improvements, we will explain the manner of operating the apparatus. The driver being seated, the main lever, L , is near his right hand. The ploughs all being in place, the team is started. Should it be necessary to lift the ploughs, either one or all, the driver can do so by carrying lever L forward, and by pressing upon the two small levers $l l$ he can drop the ploughs instantly, or if only one is required, by pressing the lever l , holding it. He can also at the same time, or otherwise, cast his hand to the right or to the left, when the ploughs will be moved in the contrary direction, for any purpose which may be requisite. While these two operations are in progress, if it should be essential to change the direction of the ploughs, he can press with his foot upon the lever t^3 , release the tongue at $t^2 t^3$, and with his left hand upon lever T^2 , move the tongue on either side, while the team will continue its direction down the furrow.

Of course, it will be understood that these are all operations which can be performed separately and independently of each other, when only one is required, or simultaneously if requisite.

Having thus fully described our invention, what we claim as new and useful therein, and desire to secure by Letters Patent of the United States, is—

1. The combination of lever L with subordinate levers $l l$, and their attachments, pawls and springs, when operating upon the sleeves $S S$, substantially as described.
2. The combination of lever L with sleeves $S S$ and shaft s , to move laterally, as substantially described.
3. The arrangement of levers $T^2 T^1$, and t , in connection with the tongue, substantially as described.
4. The use of a central plough, F , detachably arranged, in connection with the side ploughs, substantially as described.
5. The combination of lever L and its attachments, forming a combined lever, with vertical and horizontal motions, coincident when necessary and convenient, together with the adjustable devices $T^2 T^1$, and t , all operating together, substantially and for the purposes specified.

In testimony whereof, we have signed our names to this specification in the presence of two subscribing witnesses.

THADDEUS DONELY,
JOSEPH B. CRESSLER.
